UNITED STATES PATENT OFFICE

CHARLES W. BORLAND, OF MAYWOOD, ILLINOIS

VALVE SPRING RETAINER TOOL

Application filed May 12, 1932. Serial No. 610,947.

This invention relates to valve replacement and removal tools and more particularly to a means for facilitating the replacement of the keepers for the valve spring washer.

5 An object of this invention is to provide a means to prevent the losing of the valve stem keepers during the removal or replacement of these keepers about the valve stem.

Another object of this invention is to provide 10 a magnetic means which can be connected to a suitable source of current supply and which will not only facilitate the removal or replacement of the valve stem keepers but will also pick up the keepers in the 15 event they drop into the vehicle engine, thereby eliminating the necessity of taking portions of the engine apart in order to obtain the keepers.

A further object of this invention is to provide 20 a device of this kind which has adjustable means to adjust the degree of magnetism so that the device can be used to replace the valve stem keepers.

The above and various other objects and 25 advantages of this invention will in part be described in and in part be understood from the following detailed description of the present preferred embodiment, the same being illustrated in the accompanying drawing

30 wherein:

Figure 1 is a longitudinal section partly in detail and partly broken away of a device constructed according to the preferred embodiment of this invention.

35 Figure 2 is a detail top plan view of one of the valve stem keeper supporting members having a keeper mounted therein.

Figure 3 is a similar view with the keeper removed from the attachment.

40 Figure 4 is a fragmentary top plan view of the guide member for guiding the device toward the valve stem.

Figure 5 is a longitudinal section partly in detail of a further keeper attachment.

45 Figure 6 is a detail side elevation of another attachment which can be mounted on the end of this device so as to remove keepers which may drop into the casing of the engine.

50 Referring to the drawing wherein like

numerals of reference designate corresponding parts throughout the several views, the numeral 10 designates generally a handle, and the numeral 11 designates a sleeve or stem projecting forwardly of the handle 10. The 55 stem 11 also has a shaft or rod 12 secured therein by means of a securing member 13 or the like, and the outer end of this rod 12 is provided with threads 14 to removably receive the inner end portion 15 of a keeper supporting member, generally designated as 16.

This keeper supporting member 16 comprises a shank or threaded member 15 engaging the outer end of the rod 12, which 60 rod 12 is preferably made of iron which is capable of being readily magnetized and the keeper supporting member 16 is preferably 65 of relatively soft iron which is capable of being readily magnetized.

The keeper supporting member 16 also includes a plate 17 which has a slot 18 therein to loosely receive the valve stem S. An 70 upstanding rim or flange 19 is formed with the plate 17 and this flange 19 is of generally 75 arcuate construction but is provided at the center thereof with a rearwardly curved portion 20, the purpose of which will be herein-after described.

A valve stem keeper 21 is adapted to engage about the reduced lower end portion 22 of the stem S and as shown in Figure 1, the keeper 21 is adapted to seat on the plate 17 and is initially placed about the stem S by disposing the two portions of the keeper 80 in substantially V-shaped form with the apex extending rearwardly or toward the curved or bulging portion 20.

A guide rod, generally designated as 23, 85 is slidably mounted within the core or rod 12, which core is provided with a bore 24 and the outer end of the guide member 23 is provided with a segmental tappet engaging member 25. The inner end of the guide 90 member 23 has an enlarged head 26 carrying a spring 27 which holds the guide member 23 in longitudinally adjusted position within the bore 24. The guide member 23 is 95 slideable through an opening 28 provided in the 100

base 15 of the valve stem supporting member 16.

In order to magnetize the core 12 and the valve keeper supporting member 16, I have 5 provided a coil 29 which is disposed about the core 12, this coil 29 being formed of relatively fine wire which is mounted within a casing 30. An end member 31 engages the outer end of the casing 30 and abuts against 10 one end of the coil 29, and an inner end member 32 engages the inner end of the cylindrical casing or housing 30 and is secured about the core 12 in abutting relation to the outer end of the sleeve 11.

15 A resistance coil 33 is mounted within the housing 30 intermediate the inner end of the coil 29 and the end member 32, and the outer end of this resistance coil 33 is separated from the coil 29 by means of a separating 20 member 34 of non-conducting material. The coil 29 is provided with two conductors 35 and 36, which are adapted to be connected to a suitable source of current supply. The conductor 36 has a clip 37 secured to one 25 end thereof and this one end extends axially through the handle 10 and is adapted to be connected to battery or other suitable source of current supply.

A spring pressed switch 38 is interposed 30 in the conductor 35 and this switch is normally in open position so as to break the circuit to the coil 29. A conductor 39 is connected at one end to one end of the resistance coil 33 and the opposite end is connected to the 35 conductor 35 at a point beyond the switch 38. The other end of the resistance coil 33 is connected by means of a conductor 40 to the conductor 35 on the side of the switch nearest the coil 29 so that when the switch 40 38 is in its normal open position, the current from the source of supply will be shunted through the resistance coil 33 and into the coil 29, thereby reducing the power of the current to magnetize the core 12.

45 When it is desired to remove a keeper 21 from about the valve stem S, the switch 38 may be closed, thereby cutting out the resistance coil 33 and magnetizing the core 12 to a higher degree. In this manner, the keeper 21 will be firmly held on the plate 17 and will be held thereupon notwithstanding movement of the supporting member 16 laterally relative to the stem S so that the two portions of the keepers will be firmly 55 held on the plate 17.

The keeper supporting member 16a shown in Figure 5 is similar to the keeper 16 with the exception that the plate 17a is not provided with an upstanding rim. This attachment or keeper supporting member 16a may be used to remove the keeper 21 from about the valve stem S. An elongated bar 41 of longitudinally curved configuration is provided with a nut 42 which threadably engages the threaded end portion 14 of the

core 12, and this member is used where one or more portions of the keeper 21 drop into the engine casing or behind portions of the engine which cannot be readily reached by fingers or removing tools.

In the use and operation of this device, the conductors 35 and 36 may be connected to a battery or source of current supply through the clips 37 and 43. With the switch 38 in open position, the electric current will flow through the resistance unit 33 and into the coil 29, the resistance coil 33 reducing the magnetism of the core so that the tip 16 will be magnetized only to a small degree. When the valve spring is raised through the use of a valve spring compression tool 44 of conventional construction, the keeper 21 will drop onto the supporting tool 16 and the switch 38 may then be closed so as to shunt out the resistance coil 33 and magnetize the core 12 and the support 16 to a higher degree so that the handle 10 may be moved laterally of the stem S which will spread the keeper members 21 apart, but these members will be held on the support 16 by the power of the magnetism in the core 12 and the core extension or support 16.

In the placement of the keepers 21 about the valve stem S, the keepers may be placed on the support 16, as shown in Figure 2, being placed in substantially V shape. The guide 23 may be pulled outwardly to the limit provided by the enlarged stop portion or slide 26. The tappet engaging member 25 may then be engaged with the periphery of the tappet whereupon the handle 10 may be moved inwardly, and through the use of this guide member 23, the keeper supporting member 16 will be guided in the correct position with respect to the peripheral groove 22 of the valve stem S so that the keepers 21 will properly engage about the valve stem. As the handle 10 is moved inwardly with the keepers 21 about the valve stem, the periphery of the stem will force the rear portion of the keepers into the notch 20 of the flange 19 which will serve as a means to compress or close the keepers about the valve stem S. The spring compressing tool 44 may then be released so as to permit the spring to force the valve spring washer 45 downwardly and close about the keeper 21.

It is, of course, understood that various changes and modifications may be made in the details of construction and design of the above specifically described embodiment of this invention without departing from the spirit thereof, such changes and modifications being restricted only by the scope of the following claims.

What is claimed is:

1. A device as described comprising a handle, a keeper supporting member supported by the handle, means for magnetizing the member, a guide means below the member,

- and frictional means for maintaining the guide means in adjusted position relative to the handle.
2. A device as described comprising a handle, a keeper supporting member, means for magnetizing the member, means for varying the degree of magnetization of the member, a guide means below the member and frictional means for maintaining the guide means in adjusted position relative to the handle.
3. A device as described comprising a handle, a valve stem keeper supporting member, means for securing the member to the handle, means for magnetizing the member whereby to removably hold the keeper on the member, a guide means below the member and frictional means for maintaining the guide means in adjusted position relative to the handle.
4. A device as described comprising a handle, a valve stem keeper supporting member, means for securing the member to the handle, means for magnetizing the member, guide means for guiding the member during the operation of replacing a valve stem keeper, and resilient means for holding the guide means in adjusted position.
5. A device as described comprising a handle, a valve stem keeper engaging member, means for securing the member to the handle, means for magnetizing the member, means for varying the degree of magnetization of the member, and slidably guide means for guiding the member toward a valve stem during the operation of replacing a keeper about the stem.
6. A device as described comprising a handle, a valve stem keeper supporting member, a core member secured to the handle and to the member, a coil about the core whereby to magnetize the core and the member, means for varying the degree of magnetization of the member and the core, a guide means in the core and means for frictionally holding the guide means in adjusted position within the core.
7. A device as described comprising a handle, a valve stem keeper supporting member, a core carried by the handle and engaging the member, a plurality of coils disposed about the core, means for selectively interposing the coils in an electric circuit to vary the degree of magnetization of the member, a guide means in the core and means for frictionally holding the guide means in adjusted position within the core.
8. A device as described comprising a handle, a valve stem keeper supporting member, an iron core carried by the handle and engaging the member, a coil disposed about the core, conductors engaging the coil and adapted to be interposed in an electric circuit to energize the coil and magnetize the core and the member, a resistance means con-
- nected to the coil, means for shunting the resistance means whereby to vary the degree of magnetization of the member, a guide means in the core and means for frictionally holding the guide means in adjusted position within the core.
- In testimony whereof I hereunto affix my signature.
